UNITED STATES PATENT OFFICE.

OLIVER W. MOJONNIER, OF OAK PARK, ILLINOIS.

CAN-POLISHING MACHINE.

1,338,949.

Specification of Letters Patent.

Patented May 4, 1920.

Application filed September 6, 1918. Serial No. 252,913.

To all whom it may concern:

Be it known that I, OLIVER W. MOJONNIER, a citizen of the United States, residing at Oak Park, in the county of Cook, State of Illinois, have invented certain new and useful Improvements in Can-Polishing Machines; and I do hereby declare the following to be a full, clear, and exact description of the invention, such as will enable others skilled in the art to which it appertains to make and use the same.

The invention relates to a can polishing machine and more particularly to the class of automatic can polishing machines.

The primary object of the invention is, the provision of a machine of this character wherein the ends of cans for containing evaporated milk, tomatoes, corn, other vegetables or substances, will be polished under the action of brushes, which are arranged to work against the ends of the cans in parallel relation to each other transversely of the path of travel of the cans, which are moved by an endless conveyer traveling upon a track which is inclined from the receiving end to the delivery end of the machine, the brushes being prevented from catching between the cans when in motion and in the links of the conveyer.

Another object of the invention is, the provision of a machine of this character, wherein the use of elevating mechanism at both receiving and delivering ends of the machine are eliminated or dispensed with, the brushes for the polishing of the ends of the cans being operated by the up and down stroke and in parallelism with each other thereby enabling the brushes to act freely and uniformly upon the ends of the cans without subjecting the same to any lost motion, thereby avoiding any derangement of the cans in the travel of the same through the machine.

A further object of the invention is, the provision of a machine of this character, wherein the brushes are readily adjusted to accommodate therebetween different sizes of cans which are continuously fed by an endless conveyer the same being of novel form to assure the proper feeding of the cans and to avoid excessive power in the operation of the machine, the machine in its entirety being of novel form to assure the perfect working thereof.

A still further object of the invention, is the provision of a machine of this character

which is comparatively simple in construction, thoroughly reliable and efficient in its operation, automatically operated and inexpensive to manufacture. 60

With these and other objects in view, the invention consists in the features of construction, combination and arrangement of parts as will be hereinafter fully described, illustrated in the accompanying drawings 65 and pointed out in the claim hereunto appended.

In the accompanying drawing:

Figure 1, is a side elevation of a can polishing machine constructed in accordance 70 with the invention, the feed chute being shown in vertical section and a portion of the machine being broken away for illustrating the details.

Fig. 2, is a front end elevation of the 75 machine.

Fig. 3, is a rear end elevation thereof.

Fig. 4, is a fragmentary enlarged vertical transverse sectional view.

Fig. 5, is a fragmentary detailed side elevation of the guide wheel for the conveyer. 80

Fig. 6, is a view similar to Fig. 5, showing the power or driving wheel for the conveyer.

Fig. 7, is a fragmentary vertical longitudinal sectional view through the machine. 85

Fig. 8, is a detailed fragmentary transverse sectional view showing one of the brushes and its operating stem.

Fig. 9, is an outer end elevation thereof. 90

Fig. 10, is an enlarged longitudinal sectional view through the chain or conveyer.

Similar reference characters indicate corresponding parts throughout the several views in the drawings. 95

Referring to the drawing in detail, A, designates generally, the main supporting frame of the machine, which includes the base 10 from the front end of which rise short vertical posts 11, while at the rear end rise long vertical posts 12. The upper ends of the posts 11 and 12 carry inclined side sills 13, to which are connected at intervals cross sills or track supports 14 bolted or otherwise fastened thereto. Mounted 100 thereon longitudinally of the frame centrally of the same, is the inclined conveyer track or runway 15 which extends from one end to the other of the frame. Fixed to the posts 11 and 12 beneath and in spaced parallel relation to the side sills 13, are lower supplemental side sills 16 supporting medi- 110

ally thereof bearings 17 in which is journaled a driven shaft 18 disposed transversely of the frame, and this shaft supports a drive belt wheel 19 over which is trained 5 an endless driving belt chain 20 the same also being trained over a driving belt wheel 21 on the driving shaft 22 of a motor 23 preferably of the electric type, mounted and supported upon the base 10 in any suitable 10 manner.

Arranged between the supplemental side sills 16 at intervals are cross struts or braces 24 supporting risers 25 constituting supporting legs or props forming supports for 15 the track 15.

Suitably journaled at the high end of the frame A in the vertical post 12 is a driven countershaft 26 on which is mounted a sprocket wheel 27 and trained thereover is 20 an endless sprocket chain 28, the same being also trained over a sprocket pinion 29 fixed to the driven shaft 18 so that motion from the latter will be imparted to the countershaft 26 which carries and has fixed 25 thereto a driving wheel 30 preferably of octagonal shape having chain teeth 31 for meshing engagement with the links of an endless conveyer, hereinafter fully described.

At the lower end of the receiving end of 30 the frame A, and suitably journaled in the short post 11 is a horizontal shaft 32 on which is arranged a guide wheel 33, preferably octagonal shape for the endless conveyer, while the driven shaft 18 has thereon 35 an idle wheel 34 for said conveyer.

The endless conveyer comprises a flexible chain having a series of solid links 35 pivoted together at 36 and each link is formed with a recess 37 opening through the inner 40 face thereof, to receive the teeth 31 of the drive wheel 30 and the upper stretch of this chain 35 travels upon the track 15 while the lower stretch of said chain travels over the idle wheels 34, the links 35 45 of the chain being formed with cam abutments, cleats or flights 38 having concavities 39 for receiving the can to be conveyed through the machine. The width of the conveyer is less than the length of the 50 smallest size can to be introduced into the machine for exposing the ends of the cans beyond the track at each side thereof for action thereon by the brushes, hereinafter fully described.

55 Mounted on the frame and adapted to bridge the track 15 are arch members or bridge yokes 40. Supported directly over the track 15 of the conveyer, movable thereon is a retaining plank or guide 41, which 60 overhangs the cleats or flights 38 on the upper stretches of the chain 35 to retain the cans in the conveyer when being hoisted thereby upon the track 15 from the low to the high end of the machine.

65 At the lower or receiving end of the frame

A of the machine is a supply chute 42, which feeds the cans by gravitation on to the cleats 38 of the conveyer which collects the cans singly from said chute 42 and elevates the same to the high or delivery end of the 70 machine, whence, said cans are discharged from the conveyer into the delivery chute 43 to a suitable point of deposit.

The can end polishing mechanism of the machine comprises spaced pairs of reciprocating brush standards 44 arranged in parallel relation to each other and are slideable in guide brackets 45 fixed to the inner sides of the sills 13 and 16 and the lower ends of these standards 44 are loosely connected 80 through the medium of links 46 with the outer ends of rockers 47. The inner ends of the latter are pivoted at 48 to arms 49 eccentrically pivoted to wheels or disks 50 fixed to the driven shaft 18 at the ends thereof, so that the rockers 47 will be actuated for the reciprocation of the brush standards 44 for actuating the brushes herein described.

Adjustably mounted in the upper ends of 90 the standards 44 are the threaded stems of eye bolts 51 in whose eyes are engaged brush supports each including a threaded shank 52 having on its inner end a disk-like head 53 to which is adjustably fastened the stock 95 54 of a brush 55, the threaded shank being fitted with jam nuts 56 working against opposite sides of the eye bolt 51, and in this manner the shank 52 is adjustably mounted therein for moving the brush 55 laterally 100 toward and away from the cans to be polished, thereby accommodating different sizes of cans between the opposed brushes in the machine for the polishing of the ends of said cans by reciprocal action of the brushes in 105 their parallel movement up and down in the machine.

In the operation of the machine the cans are fed on the conveyer to the supply chute 42 which carries said cans upwardly of the 110 track 15 from the low to the high end of the machine. The cans travel between the brushes 55 which reciprocate in parallel relation with each other on up and down movement thereof to act upon the ends of 115 the cans for the polishing thereof, and said brushes will not become caught in the links of the chain conveyer nor will they project between the cans on the conveyer.

On the travel of the cans they are successfully polished and are subsequently delivered from the delivery chute 43 to a suitable point of deposit. It is apparent that the brushes can be renewed when the occasion requires and the necessity of elevating 125 means at the receiving and delivery ends of the machine is avoided. The can ends will be thoroughly polished by the action of the brushes prior to the discharge thereof from the machine.

From the foregoing it is thought, that the construction and the manner of operation of the machine will be clearly understood and therefore a more extended explanation 5 has been omitted. It is, however, to be understood that the applicant reserves the right to make changes, variations and modifications not in the invention such as come within the bounds of the appended claim 10 without deviating or departing from the spirit of the invention or sacrificing any of its advantages.

What is claimed is:

In a can polishing machine, the combination 15 with a supporting frame having an inclined track, can conveying mechanism movable over the track, and upright guides in the frame; of standards mounted for verti-

cal reciprocation in said guides at opposite sides of the track, eye bolts whose stems are 20 adjustable vertically in the upper ends of the standards, threaded shanks passing horizontally through the eyes of said bolts, nuts on the shanks at opposite sides of such eyes, brush stocks carried by said shanks and facing toward the ends of the cans, and driving means for moving the conveying mechanism and simultaneously reciprocating said standards.

In testimony whereof I affix my signature, 30 in the presence of two witnesses.

OLIVER W. MOJONNIER.

Witnesses:

JOHN M. DURYER,
Mrs. O. W. MOJONNIER.
